UNITED STATES PATENT OFFICE.

JESSE C. COOK, OF JEFFERSONVILLE, INDIANA, ASSIGNOR TO THE AMERICAN CREOSOTING COMPANY, OF LOUISVILLE, KENTUCKY, A CORPORATION OF INDIANA.

RAIL-LIFTING DEVICE.

Application filed July 30, 1924. Serial No. 729,103.

To all whom it may concern:

Be it known that I, JESSE C. COOK, of Jeffersonville, in the county of Clark, State of Indiana, a citizen of the United States, have invented certain new and useful Improvements in Rail-Lifting Devices; and I do hereby declare the following to be a full, clear, and exact description of the invention, such as will enable others skilled in the art to which it appertains to make and use the same.

In the art of timber impregnation, as with creosote, the timber is run into the creosoting cylinder on rails from a track system in the yard, the track within the cylinder being connectible with the yard track by an approach track or rail section which must be removed from the path of swing of the cylinder door to permit of the cylinder being closed.

It is the object of this invention to provide a simple and durable mounting for the removable track section whereby the same may be readily moved to an inoperative position with little effort on the part of the operator.

The invention further resides in the provision of a vertically swinging track section, counterbalanced to facilitate its upward movement, and having actuating means located to position the operator out of danger in the event of an accidental lowering of the track section or breaking of the counterbalance.

In the drawings, Figure 1 is a fragmentary side elevation of a creosoting cylinder depicting the removable track section in its operative position in full lines and in its inoperative position in dotted lines; and Figure 2 is a top plan view thereof.

Referring more in detail to the accompanying drawing, the creosoting cylinder 1, which is equipped with the horizontally swinging door 2, is also provided with rails (not shown) adapted to be joined to the yard rails 3 by the track section or door rails 4. These door rails are fixed at one end to a horizontally journaled shaft 5 while their opposite ends are designed to be supported by the cylinder in alignment with the cylinder rails. The shaft is extended to one side of the rails and the outer extremity of such extended end is provided with a cam 6 which is keyed to the shaft. In spaced relation to the cam 6,

an operating lever 7 is keyed to the shaft 5 for effecting turning of the shaft to raise or lower the rails. Lever 7 carries pawl 8 which cooperates with a fixed quadrant 9 to lock the rails in any desired degree of elevation.

A counterbalance device is provided to assist the operator in lifting the track section. An adjustable weight 10 is suspended from the outer end of a lever 11 which is fulcrumed on a short shaft 12, appropriately journaled in bearings supported by the building walls (not shown), the location of this shaft being well above the shaft 5 so that the lever 11 may swing in a vertical plane outwardly of the operating lever 7. The short shaft 12 also carries a second cam 13 to the sides of which the angle irons which form the lever 11 are bolted, these angle irons converging toward their opposite ends to provide a braced structure and there connecting with a plate 14 from which the weight 10 is suspended. The cams 6 and 13 are shown in the form of interrupted circular disks presenting substantially a one-fourth part of its true or concentric circumference, and the periphery of which circumference is preferably grooved, as indicated at 14^a, and they are connected by a flexible member 15, herein shown as a cable, divided between its ends and having its sections joined by an adjustable take-up device, such as a turnbuckle 16. The flexible member has its opposite ends anchored to the irregular peripheral portions of the cams 6 and 13 beyond the concentric circumference portions as indicated at 16 thus allowing the flexible member to slide over the cam portions in the operation of the counterbalance device.

In operation, when it is desired to lift the approach track section from the path of swing of the cylinder door, the operator manipulates the lever 7 to effect a clockwise rotation of the shaft 5 which elevates the door rails 4 to an upwardly inclined position, such as is indicated in Figure 1, where they are held locked by the cooperation of the pawl 8 and its quadrant 9. The manual effort on the part of the operator is materially assisted by the counterbalance device which exerts a continuous force tending to lift the rails. The counterbalance weight and the lever 7 are spaced sufficiently far from the rails to provide room be-

2
tween the lever and the rails for the operator to occupy without endangering himself in the event of accidental breakage of the rails or their operating mechanism.

5 After the door 2 has been opened the rails 4 are then lowered to the full line position by a counter-clockwise movement of the shaft and lever 7, whereby the yard and cylinder rails are connected for moving the 10 timber-carrying trucks to and from the cylinder.

This invention is a continuation in part of the copending joint application Ser. No. 660,026 filed Aug. 29, 1923 by Harold E. 15 Austin and myself.

I claim as my invention—

1. In combination with a creosoting cylinder having a swinging door, of a track section swingingly mounted to move from a position in the doorway of the cylinder to 20 a position out of the path of swing of the door.

2. In combination with a cylinder and door therefor, of an approach track section, a shaft to which the section is connected for being moved to and from operative position thereby, and means for rotating the shaft. 25

In testimony whereof I signed this specification.

JESSE C. COOK.
